UNITED STATES PATENT OFFICE

133,713

DESIGN FOR A SUCTION CLEANER OR SIMILAR APPARATUS

Ralph E. Kruck, Springfield, Mass., assignor to
Westinghouse Electric & Manufacturing Com-
pany, a corporation of Pennsylvania

Application August 14, 1941, Serial No. 102,829

Term of patent 14 years

To all whom it may concern:

Be it known that I, Ralph E. Kruck, a citizen of the United States, residing at Springfield, in the county of Hampden and State of Massachusetts, have invented a new, original, and ornamental Design for a Suction Cleaner or Similar Apparatus, of which the following is a specification, reference being had to the accompanying drawings, forming a part thereof.

Fig. 1 is a perspective view of a suction cleaner showing my design, with a handle and dust bag shown in dotted outline;

Fig. 2 is a side view in perspective with the

handle and dust bag of the cleaner omitted for convenience of illustration. The opposite side of the cleaner is substantially the same as that shown; and

Fig. 3 is a front perspective view with the handle and dust bag omitted.

The dominant features of the design reside in the casing shown in full lines on the drawings.

I claim:

The ornamental design for a suction cleaner or similar apparatus, substantially as shown and described.

RALPH E. KRUCK.
